DINNERWARE DISPLAY RACK OR SIMILAR ARTICLE

Elmer L. Reibold, Park Ridge, William W. Timpe, Prospect Heights, and Kasimer F. Panek, Broadview, Ill., assignors to E. L. Reibold Agency, Inc., Rosemont, Ill., a corporation of Illinois

Filed Apr. 11, 1967, Ser. No. 6,630

Term of patent 7 years

(Cl. D80—10)

FIG.3

FIG. 1 is a perspective view of a dinnerware display rack embodying our new design;

FIG. 2 is a reduced front elevational view thereof; and

FIG. 3 is a reduced side elevational view thereof.

The dominant features of the design reside in the portions shown in full lines.

We claim:

The ornamental design for a dinnerware display rack or similar article, substantially as shown and described.
